H. HARTMAN.
VENDING MACHINE.
APPLICATION FILED SEPT. 18, 1916.

1,275,153.

Patented Aug. 6, 1918.

Hans Harbman, Inventor,

by Frank Warren
Attorney.

UNITED STATES PATENT OFFICE.

HANS HARTMAN, OF NEW YORK, N. Y., ASSIGNOR TO AUTOMATIC VENDING MACHINE CO., OF NEWARK, NEW JERSEY, A CORPORATION.

VENDING MACHINE.

1,275,153.

Specification of Letters Patent. Patented Aug. 6, 1918.

Application filed September 18, 1916, Serial No. 120,657.

To all whom it may concern:

Be it known that HANS HARTMAN, subject of the Emperor of Austria-Hungary, residing at New York, in the county of New York and State of New York, has invented certain new and useful Improvements in Vending Machines, of which the following is a specification.

My invention relates to a vending machine, and while it has for its prime objects the production of an extremely simple construction, one which is efficient and reliable in operation and capable of manufacture at low cost, yet I aim to provide a construction particularly adapted for attachment to chairs in public places like theaters and cars; one in which the feeder mechanism is operable only in the presence of a coin; one in which the feeder is gradually advanced to successively deliver articles upon the successive insertion of proper coins and subsequent actuations; one in which spurious coins of improper denominations and size will fail to operate and one in which coins cannot be inserted after the contents have been vended.

With the above and additional objects appearing hereinafter, in view, the invention has been embodied in one preferred form as described hereinafter and illustrated in accompanying drawings in which:—

Figure 1 is a rear view of the machine with part of the closure and coöperating plate broken away to disclose details and,

Fig. 2 is substantially a central vertical sectional view through the machine.

Referring specifically to the drawings wherein like reference characters designate like or corresponding parts, a suitable casing is provided and by way of example may be substantially rectangular as shown at 10. While the machine is shown as of the vertical type, a limitation in this regard is not to be implied. The front wall of the casing, which is designated 11, as well as the side walls shown at 12 are closed and at the rear a low wall 13 is rigidly connected to the side walls. Pivoted to wall 13 as at 14 is a rear or closure wall 15. This closure may be fastened to the remainder of the casing in any convenient way; for instance, it may have an integral angle or top wall 16 by which it is releasably fastened to the wall beneath it by means indicated at 17.

Within the casing, fastened to closure 15, is a plate or wall 18 having a substantially round opening 19 and an elongated opening 20 depending therefrom. Opening or slot 20 communicates with a way or slot 21, which plate 18 partly overlaps at each side and which is provided by stamping the closure 15 outwardly at 22.

A package feeder has a block 23 slidably disposed in slot 21 and overlapped by wall 18 at 18' to prevent lateral displacement. A lug or follower 24 extends laterally from block 23 through and beyond slot 20 so as to rest upon the uppermost package of a pile of independent packages 25. The lowermost package is frictionally engaged at opposite ends by yieldable clasp fingers 26 suitably fastened, as at 27, to the side walls 12 of the casing. The other packages are supported from and above the lowermost package. When a package is vended, it falls upon the bottom wall of the casing at 28 so that it may be withdrawn through an opening 29 provided at one or both sides of the casing.

As well as the feeder, the coins are also adapted to travel in slot 21. One coin is shown at 30. The coins are inserted into a passage way 31 communicating with slot 21 and which is provided by stamping wall 15 outwardly at 32. The entrance to passage-way 31 is at one side of the machine and this passageway is properly closed by the plate 18. Opening 19 is of slightly less diameter than the coin and hence if spurious coins of a size smaller than a proper coin are inserted they will pass through opening 31 and deposit in the casing above lug 24.

Slot 21 extends to the top of the machine and a plunger 33 slides therein and through an opening 34 in wall 16. Lateral lugs 35 prevent complete withdrawal of the plunger from the casing as they abut wall 16. This plunger operates against the coins in slot 21 and to facilitate its manipulation, a handle is provided at 36.

In operation with the casing filled with packages or articles to be vended, and it is desired to purchase one of the articles, a coin of the proper denomination is inserted into passageway 31 after which plunger 33 is manually raised so that the coin will fall between the plunger and the lug 24. The plunger is thereupon depressed so as to move the coin downwardly as well as the pile of

packages to a sufficient extent to move the lowermost package out of engagement by the clasp fingers 26 and the next package into direct engagement between said clasp fingers. The released package falls upon the wall 28 and from this position may be removed by the hand of the vendee inserted through opening 29. Successive vendees repeat the described operation until the contents of the machine have been vended at which time feeder 23 will be in the bases of slots 20 and 21 and the coins will fill the slot 21 with the uppermost coin occupying the position shown in Fig. 1 so that sufficient space is not provided to receive a coin when the goods have been sold. This feature insures honest dealing between the owner of the machine and the public. To remove the coins, closure 15 is opened. After removal, the supply of goods may be replenished and the machine set for further operation. As previously stated small spurious coin will travel through slot 19 into the casing space above lug 24.

As merely the preferred embodiment of the invention has been illustrated and de-

scribed it is to be understood that changes may be resorted to.

I claim:

A vending machine comprising a casing to receive a plurality of articles to be vended, means engaging frictionally the lowermost article, a cover for said casing having a coin slot and a coin inlet at one side leading to said coin slot, an article pusher arranged slidably within said coin slot so as to support the first coin inserted, said coin slot overlapping only slightly coins of proper diameter at both sides, being open inwardly to allow smaller coins to fall into said casing from said coin slot, a slideable plunger extending from the top of said cover and guided within the upper part of the coin slot so as to move the article pusher through the medium of said coin, an extension on said article pusher extending from the coin slot into the casing and resting normally upon the uppermost article and a delivery opening arranged at the lowermost part of the casing.

In testimony whereof I affix my signature.

HANS HARTMAN.
